CELL CULTURE VESSEL OR THE LIKE

Robert Dragotta, Vineland, N.J., assignor to
Bio-Research Glass, Inc., Vineland, N.J.

Filed Oct. 2, 1974, Ser. No. 511,188

Term of patent 14 years

Int. Cl. D24—02

U.S. Cl. D32—1 R

FIG. 1

FIG. 2

FIG. 3

FIG. 1 is an elevational view of a cell culture vessel showing my new design;

FIG. 2 is a top plan view thereof; and
FIG. 3 is a bottom plan view thereof.

I claim:

The ornamental design for a cell culture vessel or the like, as shown.
